UNITED STATES PATENT OFFICE.

GEORGE P. ERHARD, OF BROOKLINE, MASSACHUSETTS, ASSIGNOR TO THE STAFFORD COMPANY, OF READVILLE, BOSTON, MASSACHUSETTS, A CORPORATION OF NEW JERSEY.

BELT-HOLE GUARD.

1,233,267.

Specification of Letters Patent.

Patented July 10, 1917.

Application filed July 2, 1915. Serial No. 37,715.

To all whom it may concern:

Be it known that I, GEORGE P. ERHARD, a citizen of the United States, residing at Brookline, in the county of Norfolk, State 5 of Massachusetts, have invented a certain new and useful Improvement in Belt-Hole Guards, of which the following is a specification, reference being had therein to the accompanying drawings.

10 The invention is an improvement in the covers, casings, or curbs, known sometimes as belt-hole guards, which are applied to the floors of buildings in connection with holes through which driving belts or bands 15 of machinery stretch from one story to another above or below, and which are designed to protect such holes and close them more or less completely while leaving passageway for the belts or bands.

20 The invention provides a belt-hole guard of novel construction having one or two cover-portions relatively adjustable so as to enable the lips of the opening or mouth occupied by the belt or band to be spaced at 25 the right distance apart. The adjustability provides for locating either or both of the said lips as close as may be desired to the belt or band. It provides for enabling the 30 to be varied to suit that of the portion of belt or band which occupies the belt-hole and the said opening or mouth.

An illustrative embodiment of the invention is represented in the drawings, in which 35 latter,—

Figure 1 is an end elevation of the said embodiment, showing also a portion of belt or band which stretches through the guard.

Fig. 2 is a plan view thereof.

40 The said embodiment comprises a shell-like body 1, a foot or flange 2, and opposite cover-portions 3, 3. The said cover-portions are mounted upon the body 1 at opposite sides of the position of the portion of belt 45 or band *a* that stretches through the guard. The foot or flange 2 extends around the base of the body 1 and stands out therefrom, and is adapted to be placed upon or against the surface of the floor, wall, or casing in which

50 is made the belt-hole that is to be covered and protected. The fastenings by which the guard is fixed in place will engage usually with the said foot or flange. The latter is furnished with holes 2^a, 2^a, to receive the 55 said fastenings, which may be screws or

bolts. The height of the body is to be sufficient to meet the general requirements, as for instance to prevent water or dirt from the floor from entering the opening or mouth of the guard, as well as to prevent dirt from 60 being swept upon the top of the guard and into the said opening or mouth. The two side-walls of the body which are parallel with the transverse surfaces of the belt are at a suitable distance from each other to 65 allow for a reasonable range of variations in the relative position of the belt or band between them. The two cover-portions 3, 3, are connected with the upper part of the body adjacent the said two side-walls, and 70 project inward therefrom toward each other, with their rounded lips 3^a, 3^a, approached more or less closely to the surfaces of the belt or band *a*. Each cover-portion is provided with an end-wing 5 or 5^a at each end 75 thereof. Each end-wing extends at an angle from the corresponding end of the cover-portion, close alongside an end-wall of the body, and overlapping said end-wall.

The adjustability of the cover-portions is 80 provided for by hinging the cover-portions to the body. The hinging is effected in the present instance by means of pivotal pins or pintles 6, 6, passing through the upper portion of the body at opposite sides of the 85 opening or mouth for the belt or band, and also through holes in the end-wings of the cover-portions, as shown. The pivotal pins or pintles are held in place by means of a head upon one end of each thereof outside 90 the corresponding end-wing, and a washer 7 and cotter-pin 8 applied to the other end of each, outside of the corresponding end-wing. To prevent interference of the inner portions of the end-wings through engagement with each other as the cover-portions are swung in making required adjustments, the proximate edges of the end-wings 5, 5, at the front end of the guard in Fig. 1 are 95 curved concentrically with the pivots 6, 6, 100 as shown in Fig. 1. The wings 5^a, 5^a, at the other end of the guard do not extend far enough inward from the pivotal pins or pintles to interfere with each other.

Being flexibly combined with the body 1 105 by being hinged to the latter, the cover-portions 3, 3, may be adjusted by swinging them about their pivotal axes so as to locate the lips 3^a, 3^a, and the opening or mouth between them, in the desired position with relation to 110

the belt or band *a* so as thereby to suit the position of the belt or band within the belt-hole; and also so as to vary the width of the opening or mouth between the said lips as well as the closeness of approach of the lips to the surfaces of the belt or band. The rounded lips obviate injury to the belt or band from contact of the latter with the lips. The mouth or opening may be made by adjustment of a width between the lips just sufficient to provide for the traveling movement of the belt or band. With the adjustable cover-portions I combine convenient means of adjustment. Satisfactory provisions for this purpose are shown in the drawings, such provisions comprising bolts 9, 9, seated in holes in one end-wall of the body 1 and passing through slots 10, 10, in the adjacent end-wings 5, 5, the threaded portions of the said bolts receiving upon them outside of the said end-wings washers 11 and nuts 12 by means of which the end-wings are clamped against the end-wall of the body. The slots 10, 10, are curved concentrically with the pivotal pins or pintles 6, 6, so as to provide for swinging movement of the cover-portions after the nuts 12, 12, have been loosened. The two cover-portions are independently adjustable. In some cases the desired relative adjustment and results may be secured by adjustment of one cover-portion and its lip. The construction may if desired be varied in different minor respects, and other means of adjustment may in some cases be employed.

I claim as my invention:—

1. A belt-hole guard comprising a shell-like body through which a belt or band passes, and a cover-portion provided with a lip constituting one side of an opening or mouth for the said belt or band, a pivotal mounting adapting the cover-portion to be swung to adjust the said lip toward or from the belt or band, and means for securing the cover-portion in adjusted position.

2. A belt-hole guard comprising a shell-like body through which a belt or band passes, opposite cover-portions each provided with a lip constituting one side of an opening or mouth for the said belt or band, pivotal mountings adapting the cover-portions respectively to be swung to adjust the said lips toward or from each other and the belt or band, and to adjust the opening or mouth to one side or the other, and means for securing the cover-portions in adjusted position.

3. A belt-hole guard comprising a shell-like body through which a belt or band

passes, a cover-portion provided with a lip 60 constituting one side of an opening or mouth for the said belt or band and also provided with end-wings overlapping the ends of said body, a pivotal mounting adapting the cover-portion to be swung to adjust the said 65 lip toward and from the belt or band, and means engaging with an end-wing for securing the cover-portion in adjusted position.

4. A belt-hole guard comprising a shell-like body through which a belt or band 70 passes, cover-portions provided with lips constituting opposite sides of an opening or mouth for the said belt or band, the said cover-portions provided with end-wings overlapping the ends of the body, pivotal 75 mountings adapting the said cover-portions to be swung to adjust the respective lips toward or from the belt or band and each other and also so as to vary the position of the opening or mouth, and means engaging 80 with end-wings for securing the cover-portions in adjusted position.

5. A belt-hole guard comprising a body-portion through which a belt or band passes, a cover-portion provided with a lip 85 constituting one side of an opening or mouth for the said belt or band and also provided with end-wings overlapping the ends of said body-portion, one of the overlapping parts having a curved slot therein, a pivotal 90 mounting adapting the cover-portion to be swung to adjust the said lip toward and from the belt or band, and a bolt working in said slot and serving to secure the cover-portion in adjusted position.

6. A belt-hole guard comprising a body-portion through which a belt or band passes, cover-portions provided with lips constituting opposite sides of an opening or mouth for the belt or band, and with end-wings 100 overlapping the ends of the body-portion, pivotal mountings adapting the said cover portions to be swung to adjust the respective lips toward or from the belt or band and each other and also so as to vary the position of the opening or mouth, one of the overlapping parts in connection with each cover-portion having a curved slot therein, and bolts working in the curved slots and serving to secure the cover-portions in ad- 105 justed positions.

In testimony whereof I affix my signature in presence of two witnesses.

GEORGE P. ERHARD.
